UNITED STATES PATENT OFFICE

105,841

DESIGN FOR A STEAMSHIP

Paul W. Chapman, Greenwich, Conn.

Application April 23, 1936, Serial No. 62,258

Term of patent 3½ years

To all whom it may concern:

Be it known that I, Paul W. Chapman, a citizen of the United States, residing at Greenwich, in the county of Fairfield and State of Connecticut, have invented a new, original, and ornamental Design for Steamships, of which the following is a specification, reference being had to the accompanying drawings, forming part thereof.

Fig. 1 is a side elevation of a steamship showing my new design, with the stacks elevated.

Fig. 2 is a similar view, with the stacks retracted and with the masts and railings in the lowered position.

Fig. 3 is a top plan view, and
Fig. 4 is a rear elevation.

Fig. 5 is a diagrammatic sectional view taken on the line 5—5 of Fig. 2.

The lifeboats shown on the sides are a unitary part of the design, being secured in place as shown.

I claim:—

The ornamental design for a steamship, as shown and described.

PAUL W. CHAPMAN.
